United States Patent Office

Des. 186,251
Patented Sept. 29, 1959

186,251

AIRPLANE

Omer G. Lantieri, Hartford, Conn.

Application December 11, 1957, Serial No. 48,868

Term of patent 14 years

(Cl. D71—1)

Fig. 1

Fig. 2

Fig. 3

Figure 1 is a perspective view of an airplane showing my new design;

Figure 2 is a front elevational view;

Figure 3 is a rear elevational view;

Figure 4 is a top plan view; and

Figure 5 is a side elevational view of the same.

I claim:

The ornamental design for an airplane, as shown.
